UNITED STATES PATENT OFFICE.

MATHEW YOUNG, OF BEATRICE, NEBRASKA.

ELEVATOR FOR BINDERS.

1,102,846.

Specification of Letters Patent.

Patented July 7, 1914.

Application filed June 11, 1913. Serial No. 773,089.

To all whom it may concern:

Be it known that I, MATHEW YOUNG, a citizen of the United States, residing at Beatrice, in the county of Gage, State of Nebraska, have invented certain new and useful Improvements in Elevators for Binders; and I do hereby declare the following to be a full, clear, and exact description of the invention, such as will enable others skilled in the art to which it appertains to make and use the same.

This invention relates to elevators for binders and has for an object to provide a novel elevator which may be attached to the sides of the binder elevator after removal of the binding mechanism in order to adapt the machine for use in harvesting grain that is too short to bind, the said grain being carried by said attached elevator to a hay rack at one side of the machine so that the grain may be stacked loose.

A further object is to provide novel means for attaching the elevator for upward swinging movement to the sides of the binder elevator casing.

A still further object is to provide a novel bracket for journaling the actuating shaft of the elevator, such bracket having a slip connection with the binder elevator casing side to accommodate the bracket to the movement of the actuating shaft in an arc about the pivot shaft of the elevator when the latter is raised or lowered.

With the above objects in view the invention consists of certain novel details of construction and combination of parts hereinafter fully described and claimed, it being understood that various modifications may be made in the minor details of construction within the scope of the appended claim.

In the accompanying drawings illustrating this invention:—Figure 1 is a front elevation of a binder with my improved elevator attached thereto. Fig. 2 is a plan view of the elevator and adjacent parts of the binder to which the elevator is attached. Fig. 3 is a longitudinal sectional view through the elevator. Fig. 4 is a fragmentary side elevation showing the connection of the actuating shaft bracket with the machine side. Fig. 5 is a view similar to Fig. 4 showing the position of the parts when the elevator is raised. Fig. 6 is a sectional view on the line 6—6 Fig. 4. Fig. 7 is a sec-

tional view on the line 7—7 Fig. 4. Fig. 55 is a side elevation of the windlass.

Referring now to the drawings in which like characters of reference designate similar parts, 10 designates in general a conventional binder with the binding mechanism removed.

The elevator comprising the subject matter of this invention is designated in general by the numeral 11 and is shown attached to the sides 12 of the binder elevator 13. 65 The elevator 11 comprises a casing 14 open at both ends and within the casing is disposed a pair of endless carriers 15 and 16 that serve to carry the grain therebetween from the attached end of the elevator to the 70 free end of the elevator and there discharge it into a hay rack or other vehicle for its reception. A bail 17 is secured to the free end of the elevator and a block and tackle designated in general by the numeral 18 is 75 secured to the bail and to a hook 19 that is bolted as shown at 20 to that frame bar 21 of the machine which traverses the machine elevator 13 and supports the machine reel 22 and controlling devices of the machine. 80 The tackle end after being rove through the upper block is attached to a windlass 23 that is secured to a cross bar 24 carried at the upper end of the machine elevator 13, the windlass drum having its shaft equipped 85 with ratchet controls 25 and carrying a lever 26 for winding or unwinding the tackle whereby to raise or lower the elevator.

For hingedly attaching the elevator 11 to 90 the sides 12 of the machine elevator 13, a pivot shaft 27 is journaled in bars 28 that are bolted or otherwise rigidly secured to the sides of the elevator 11, and a pair of attaching bars 29 are bolted to the sides 12 of 95 the machine elevator and have suitable openings near the free ends which pivotally receive the shaft 27 outside of the bars 28 as shown. For actuating the endless carriers of the elevator 11, the lower roller of the 100 upper endless carrier is equipped with a gear 30, and the lower roller of the lower elevator is equipped with an integral shaft 31 that carries a gear 32 which meshes with the gear 30 whereby both endless carriers are driven 105 so that their confronting laps travel upwardly. The shaft 31 is extended considerably beyond the gear 32 and is equipped with

a driving gear 33 in the nature of a sprocket which meshes with the chain drive 34 of the machine as shown and is driven by the latter to drive the endless carriers of the elevator 5 11. For reinforcing the driving shaft 31 against distortion, a skeleton triangular shaped bracket 35 is provided at the apex with an opening 36 which receives the drive shaft, and is provided in the base with slots 10 37 through which and slots 38 formed in the sides 12 of the machine elevator at right-angles to the slots of the bracket, pins 39 are passed. The bracket 35 is disposed above one of the securing bars 29 as shown 15 in Figs. 4 and 5, and when the elevator 11 is rocked up or down on the pivot shaft 27, the pin and slot connections of the bracket with the sides 12 permit of the bracket sliding in an arc to facilitate such movement, 20 while at the same time the bracket reinforces the free end of the drive shaft 31 against vibration so that displacement or injury to this shaft during such rocking movement of the elevator is positively prevented. 25 From the above description it will be seen that I have provided an extremely simple elevator which may be easily applied to ordinary binders now in use without extensive alterations, and may be easily and quickly

rocked up and down to accommodate the elevator to the height of the load as it grows on the hay rack.

What is claimed, is:—

The combination with a support including opposite sides, of an elevator hinged to said sides, means for rocking the elevator upwardly and downwardly, a drive shaft for the elevator, a shaft below said drive shaft carried by said sides and operatively connected to said elevator and forming a pivot 35 upon which the elevator is rocked upwardly and downwardly, a bracket journaling said drive shaft and disposed above said pivot shaft, there being aligned slots formed in 40 said bracket, there being furthermore parallel slots formed in said sides at rightangles to said bracket slots, and pins passed through said bracket slots and said slots of the sides and permitting of said bracket moving in an arc during rocking of said 45 elevator, said bracket reinforcing said bracket shaft against distortion.

In testimony whereof, I affix my signature, in the presence of two witnesses.

MATHEW YOUNG.
